UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

1,408,009.

Specification of Letters Patent. Patented Feb. 28, 1922.

Application filed July 15, 1919. Serial No. 310,911.

To all whom it may concern:

Be it known that I, ALFRED G. F. KUROWSKI, a citizen of the United States, formerly a citizen of Germany, residing in Brooklyn Borough, in the county of Kings, city and State of New York, have invented certain new and useful Improvements in Typewriting Machines, of which the following is a specification.

10 This invention relates to typewriting machines, and is herein disclosed as modifying the line-spacing mechanism of an Underwood standard typewriting machine.

In rapid line-spacing of the revoluble platen, there is sometimes such sudden starting and stopping of the platen that the paper held against the platen by the feed-rolls may slip, resulting in faulty line-spacing.

According to the present invention, an excessively rapid operation of the usual line-space lever need not start the platen at the same speed as the line-space wheel, thereby minimizing or avoiding the liability of the work-sheet to feed irregularly, and when the line-spacing operation is finished the platen may come to rest more slowly. The line-space wheel may be for this purpose adapted to start ahead of the platen, or to revolve to a small extent independently of the platen, but nevertheless it tends to turn the platen with it. Hence, the rapid starting of the line-space wheel may start the platen slowly, and the sudden arresting of the line-space wheel will not simultaneously arrest the platen but will allow it to continue to turn more slowly until the two resume their normal relation.

To effect this result, the line-space wheel may be journaled loosely upon the platen axle, and may be connected to said axle by a cam and a spring-pressed dog or follower, the spring and dog tending to make the line-space wheel and the platen turn together, but the dog slipping upon the cam if the line-space wheel is started too rapidly. The spring therefore gages or determines the speed at which the platen may be started to rotate, and also is effective to restore the normal position of both the slipping dog and the platen relatively to the line-space wheel.

Other features and advantages will hereinafter appear.

In the accompanying drawings,

Figure 1 is a perspective view of one end 55 of an Underwood platen shift frame with

parts largely broken away, and showing the present invention as applied thereto.

Figure 2 is an end sectional view of the parts shown in Figure 1, with the parts positioned as occurs in an extremely rapid 60 operation of line-spacing.

Figure 3 is a view similar to Figure 2, but showing the parts at rest at the close of a line-spacing operation.

Figure 4 is a side view, partly in section, 65 of the line-space wheel and its connections to the platen axle.

Figure 5 is a perspective view of the line-space wheel, the pawl and spring, the parts being spaced apart to show their details 70 clearly.

Figure 6 is a similar perspective view of the hub on the platen axle on which the line-space wheel may be journaled.

In the ordinary operation of typewriting, 75 a work-sheet, not shown, is held against the platen 10 by means of feed-rolls 11 and 12, and is adapted to be line-spaced by actuation of the line-space handle 13, which is pivoted upon the carriage at 14, and is adapted to 80 actuate a slide 15 mounted upon the shift frame 16. Upon the actuation of the handle 13, the slide 15 moves rearwardly from the Figure 1 position against the tension of its spring 17 through the Figure 2 position 85 to the Figure 3 position, in which the pawl 18, pivoted at 19 upon the slide 15, is arrested by an overthrow stop 20, which is adapted to be struck by an extension 21 of the pawl having a cam surface which in 90 arresting it forces the pawl downwardly into the teeth of the line-space wheel 22. The line-space wheel normally tends to turn with a hub 23, which is normally fast to the platen axle 24, being held thereto by the 95 usual Underwood platen release clutch 25, one form of which is shown in the patent to Helmond, No. 1,225,331, dated May 8, 1917.

The line-space wheel 22 is journaled upon 100 a peripheral surface 26, on the hub 23, which is provided with a ledge or rabbet 27 to hold the line-space wheel against a ledge 28 formed by a plate or disk 29 also forming part of the hub and held to the main part 23 105 of the hub by screws 30, of which there may be three symmetrically disposed around the axle 24. The plate 29 is formed integral with the collar 31, which extends out from the clutch 25, and which, in some forms of 110

the machine, is fast to or integral with the line-space wheel 22, and which is adapted to be locked to the axle 24 by the usual finger-piece 32. To cause the line-space wheel to tend to turn as a unit with the platen and its axle 24, the plate 29 is provided with a V-shaped depression 33, in which is adapted to fit the correspondingly faced end or nose 34 of a pawl 35, which is pivoted upon the line-space wheel at 36, and which is held in the notch or depression 33 by a rather strong spring 37.

In the form of the device herein illustrated, the spring 37 is formed as a flat spring lying just outside the periphery of the plate 29, being held in place by a screw 38 and a pin 39, and being flat so that it underlies the tail 40 of the pawl 35, and when lying flat against the periphery of the plate 29 forms a stop for the pawl 35 as its nose swings outward. If the line-space lever 13 is actuated violently, the pawl 35 is started so rapidly by the line-space wheel that its nose 34 rides out of the notch 33 upon a cam surface 41 forming an extension of the plate 29 until the tail 40 is arrested against the spring. After the tail 40 is thus arrested, the line-space wheel and the hub 23 turn together until the line-space wheel is arrested by the pawl 18 in striking the stop 20, and then the platen, continuing to turn by inertia aided by the spring 37, moves forward from the Figure 2 position to the Figure 3 position, and is arrested by the nose of the pawl which bears against a steep slope 42 of the notch 33. The platen comes to rest in its proper position because the spring 37 acting on the pawl centers it there, and the line-space wheel 22 is in the meantime held at the proper position by the usual spring detent 43. Upon release of the line-space handle, the spring 17 returns it and the slide and pawl 18 to their normal positions ready for the next line-spacing operation, the detent 43 in the meantime holding the line-space wheel at its proper position.

Variations may be resorted to within the scope of the invention, and portions of the improvements may be used without others.

Having thus described my invention, I claim:

1. In a typewriting machine, the combination with a revoluble platen and a line-space lever, of a line-space wheel, a pawl driven by said lever for driving said wheel, an axle fast to said platen, a disk fast to said axle, a second pawl pivoted to said wheel, a cam on said disk against which said second pawl bears, a spring tending to swing said second pawl against said cam to advance the platen, and a device to limit the travel of the second pawl on the cam to cause the line-space wheel to positively drive the disk when the limit of travel of the second pawl is reached.

2. In a typewriting machine, the com-

bination with a revoluble platen and a line-space lever, of a line-space wheel, a pawl driven by said lever for driving said wheel, an axle fast to said platen, a disk fast to said axle, a second pawl pivoted to said wheel, a cam on said disk against which said second pawl bears, a spring tending to swing said second pawl against said cam to advance the platen, and a tail upon said second pawl adapted to be positively arrested by part of said disk to cause the line-space wheel to positively drive the disk after the pawl has tended to turn the disk.

3. In a typewriting machine, the combination with a revoluble platen and an axle to which it is fast, of a hub on said axle, a line-space wheel journaled on said hub, a cam, a pawl having a follower cam nose forming the connection between the wheel and the hub, a detent for said line-space wheel, a line-space pawl for driving said wheel, and a spring effective on the first pawl tending to force the pawl to one end of the cam to advance the platen.

4. In a typewriting machine, the combination with a revoluble platen and an axle to which it is fast, of a hub on said axle, a line-space wheel journaled on said hub, a cam, a pawl having a follower cam nose forming the connection between the wheel and the hub, a detent for said line-space wheel, a line-space pawl for driving said wheel, a spring effective on the first pawl tending to force the pawl to one end of the cam to advance the platen, and means to limit the travel of the pawl on the cam in each direction.

5. In a typewriting machine, the combination with a revoluble platen and an axle to which it is fast, of a hub on said axle, a line-space wheel journaled on said hub, an extension of said hub forming a cam, a follower upon said wheel to bear upon the cam, a spring pressing said follower to advance the platen, and means limiting the travel of the follower upon the cam.

6. In a typewriting machine, the combination with a revoluble platen and an axle to which it is fast, of a hub on said axle, a line-space wheel journaled on said hub, an extension of said hub forming a cam, a follower comprising a nose normally caught in a depression of said cam and pivoted upon the wheel to bear upon the cam, a spring normally holding the follower in the depression, and tending to return the follower to the depression to advance the platen, and a stop for said follower to limit its travel to cause the follower to positively move the platen.

7. In a typewriting machine, the combination with a revoluble platen and an axle to which it is fast, of a hub on said axle, a line-space wheel revoluble on said axle, a pawl pivoted on said wheel and normally resting

in a depression in said hub, a cam forming part of said hub, a spring tending to swing said pawl against the cam to cam it into the depression, and a tail for said pawl 5 adapted to strike said hub to limit the movement of the wheel relatively to the axle.

8. In a typewriting machine, the combination with a revoluble platen and an axle to which it is fast, of a hub on said axle forming 10 a journal, a line-space wheel adapted to turn on said journal, extensions of the hub forming guides for the line-space wheel, a pawl pivoted on the wheel adapted to lie in a depression on one extension, a tail of said 15 pawl normally standing clear of the extension, and a spring for holding the pawl in the depression.

9. In a typewriting machine, the combination with a revoluble platen and an axle to which it is fast, of a hub on said axle forming 20 a journal, a line-space wheel adapted to turn on said journal, extensions of the hub forming guides for the line-space wheel, a pawl pivoted on the wheel and having a 25 double cam nose adapted to fit in a depression on one extension, a tail of said pawl normally standing clear of the extension and adapted to strike the extension after a 30 limited throw, and a spring returning said nose to position the platen relatively to the line-space wheel.

10. In a typewriting machine, the combination with a revoluble platen and an axle to which it is fast, of a line-space wheel 35 revoluble on said axle, a hub for said wheel forming a journal for it and comprising a rabbet to form a ledge to hold it in place and fast to the axle, a plate adapted to form another ledge to hold the wheel in place, a 40 pawl pivoted upon the wheel comprising a nose adapted to rest in a cam depression in one of the ledges, a cam extension of that ledge to co-operate with the nose, a spring tending to hold the nose in the depression, 45 and a tail of the pawl adapted to limit the throw of the wheel in advance of the hub.

11. In a typewriting machine, the combination with a revoluble platen and an axle to which it is fast, of a line-space wheel 50 revoluble on said axle, a hub for said wheel forming a journal for it and comprising a rabbet to form a ledge to hold it in place and fast to the axle, a plate adapted to form another ledge to hold the wheel in place, a 55 pawl pivoted upon the wheel comprising a nose adapted to rest in a cam depression in

one of the ledges, a cam extension of that ledge to co-operate with the nose, a flat spring lying upon the periphery of one of the ledges, and a tail of the pawl overlying 60 the spring and the periphery and adapted to be arrested by the spring striking the ledge to limit the throw of the wheel in advance of the hub.

12. In a typewriting machine, the combination with a revoluble platen, of an axle therefor, a hub mounted upon said axle, a line-space wheel mounted for independent movement upon said hub, an extension of said hub comprising a plate having a cam- 65 surface, a pawl pivoted upon said line-space wheel having one end in contact with the cam-surface and the other end free, and a spring fixed to said line-space wheel and having its free end pressing against the free 70 end of the pawl to force the opposite end of the pawl against the cam-surface, so that movement of said line-space wheel forces one end of the pawl upward on said cam- 75 surface, and forces the free end of the pawl 80 downward against the tension of the spring until it contacts with the cam-surface plate to lock the line-space wheel to said plate.

13. In a typewriting machine, the combination with a revoluble platen, of an axle 85 therefor, a hub mounted upon said axle, a line-space wheel mounted for independent movement upon said hub, an extension of said hub comprising a plate having a cam- 90 surface and a notch where the cam-surface begins, a pawl pivoted on said line-space wheel having one end resting in said notch and the other end free, and a spring fixed to said line-space wheel and having its free end pressing against the free end of the 95 pawl to force the opposite end of the pawl into the notch, so that movement of said line-space wheel forces one end of the pawl out of the notch and upward on said cam- 100 surface, and forces the free end of the pawl downward against the tension of the spring until it contacts with the cam-surface plate to lock the line-space wheel to said plate, 105 and cessation of movement of the line-space wheel forces the pawl into the notch due to the tension of the spring, thus rotating the platen a small additional amount.

ALFRED G. F. KUROWSKI.
